TAMPING TOOL FOR PREPARING TISSUE BLOCKS FOR HYSTOLOGY AND THE LIKE

Ruth M. Dole, 19791 Kingswood Lane,
Huntington Beach, Calif. 92646

Filed Apr. 14, 1969, Ser. No. 16,734

Term of patent 14 years

Int. Cl. D24—03; D8—02

U.S. Cl. D83—12

FIG. 1 is a perspective view of a tamping tool for preparing tissue blocks for hystology and the like, showing my new design;

FIG. 2 is a side elevational view thereof;

FIG. 3 is an end view thereof;

FIG. 4 is a fragmentary perspective view showing the tamping end portion of a modified embodiment of the tamping tool illustrated in FIG. 1;

FIG. 5 is an end elevational view of the tamping end portion shown in FIG. 4;

FIG. 6 is a view similar to FIG. 4 showing the tamping end portion of a modified embodiment; and

FIG. 7 is an end elevational view of the tamping end portion shown in FIG. 6.

I claim:

The ornamental design for a tamping tool for preparing tissue blocks for hystology and the like, as shown and described.
